ELIJAH C. SEARS, OF CRYSTAL LAKE, ILLINOIS.

Letters Patent No. 63,757, dated April 9, 1867.

IMPROVEMENT IN FARM GATES.

The Schedule referred to in these Letters Patent and making part of the same.

TO ALL WHOM IT MAY CONCERN:

Be it known that I, ELIJAH C. SEARS, of Crystal Lake, in the county of Henry, and State of Illinois, have invented a new and useful Improvement in Farm Gate; and I do hereby declare that the following is a full, clear, and exact description thereof, which will enable others skilled in the art to make and use the same, reference being had to the accompanying drawings, forming part of this specification, in which—

Figure 1 is a side view of a fence with my improved gate suspended to it.

Figure 2 is a vertical cross-section taken in the line $x x$, fig. 1.

Figure 3 is a vertical cross-section taken in the line $y y$, fig. 1.

Similar letters of reference indicate like parts.

This invention relates to an improvement in the construction of farm gates for board fences, which, instead of swinging on hinges, slide on rollers and guides for opening and closing. It is very simple and cheap in its construction, and works well at all seasons of the year, not being obstructed by snow and ice on the ground, which often prevent swing-gates from opening and closing freely.

A represents a panel of a board fence; B the gate attached to it. The gate B is made of four or any desirable number of boards like those of which the fence A is made. The gate is made about fifteen feet long. The boards are fastened by cleats or upright cross-bars, also made of the same plank, properly bolted together, the cleat a on the front end of the gate being placed on the outside, and the rear cleat b being placed on the inside of the gate, as shown in fig. 1. One or more intermediate cleats, c , can be fastened on the gate to stiffen and strengthen it, as desired. The cleat b at the rear end of the gate projects about three inches above the top board d of the fence A. On the inside of this cleat, next the fence, is bolted securely a double iron guide, e , which is turned over top and bottom, so that the upper end hooks over the upper edge of the board d , and the lower end hooks over the lower edge of the same board in such manner that the hooked ends can move freely on the inside of the board and act as a guide to clasp and hold the gate close to the fence when it slides back and forth to open and shut. This double guide e contains a friction-roller on each end, the upper roller g resting on the upper edge of the board d , and the lower roller g^1 bearing up against the lower edge of the board d , by which arrangement of the rollers the rear end of the gate is supported, and will travel readily to and fro upon the board d . In order that the guide e may pass the centre post h in the panel of the fence A, a notch, i , is cut in the inside of the post, as shown in fig. 3. An upright board cleat, k , is fastened on outside of the fence over the front post of the panel A, having single guides at bottom and top. The upper guide m hooks over the edge of the upper board of the gate, and bears directly upon it, while the lower guide m' hooks over the lower board of the gate and carries a roller, g^2 , on which the lower edge of the board rests, as shown in figs. 1 and 2.

By this arrangement of the guides and friction-rollers it is obvious that the gate B may be easily moved backward and forward on the panel of fence A for opening and closing; and as the gate is made fifteen feet long, when it is closed, ten feet or two-thirds of its length only will move out to fill the ordinary gate entrance, and five feet will remain on the panel of fence to balance and support the gate. It will be limited in its movement by any suitable catch.

Having thus described my invention, what I claim as new, and desire to secure by Letters Patent, is—

1. In the construction of a board gate, I claim the arrangement of the double guide e and the friction-rollers g g^1 , in the rear cleat b , in combination with the upper board d of the fence A, operating as herein described.

2. I also claim the single guides m m' at the top and bottom of the cleat k , in combination with the roller g^2 and the upper and lower boards of the gate B, arranged and operating as herein set forth.

3. I also claim the notch i in the centre-post h , to clear the double guide e when the gate is opened or closed, as herein described.

ELIJAH C. SEARS.
